 a corporation of Ohio

Application August 20, 1942, Serial No. 455,421

12 Claims. (Cl. 214—95)

1

This invention pertains to article handling and hoisting equipment of the dual drum type which is capable of a wide range of general application, but which is especially useful for loading bombs into the bomb bay of an airplane, and analogous purposes.

Obviously, the elevation and stowing of loaded bombs which weigh from one hundred to two thousand pounds or more each necessitates careful handling and accurate manipulation to avoid concussion or premature dropping of the bomb. Hand operation of bomb hoisting apparatus as heretofore commonly employed is slow and laborious, and requires a long time as compared with the present power driven apparatus. In the present instance electric motive means is ordinarily employed for the hoist apparatus, but for emergency use an alternative manual operating mechanism is provided. Coordinated safety devices prevent retraction of the cable in event of failure of the electrical power supply or failure of the human factor in manual operation.

As herein illustrated, the preferred embodiment of the invention includes a pair of independently revoluble winding drums onto which are wound the opposite ends of a single hoist cable common thereto, having therein a medial bight. The drums are operable in unison or differentially by optionally selective electric motor or hand crank actuating means. Associated with the winding drums is brake mechanism automatically effective alternately with either of the optional actuating mechanisms. The brake mechanism becomes automatically effective to hold the drums at rest with the load in elevated position upon failure of the electric current supply or interruption of the motor energizing circuit. The manual actuating means may be operatively engaged and maintained in driving condition only so long as the brake mechanism is manually maintained ineffective, and upon failure of the operator to so hold the brake mechanism, the latter is reengaged to arrest the drums and hold the load, and the manual actuating device is automatically disengaged. By unison rotation of the drums to retrieve or pay out the connected cable ends uniformly, the bomb or other work load suspended in the bight of the cable may be raised or lowered. However, by differential rotation of the drums the suspended work body or bomb may be rotated in either direction as may be necessary to present a hanger eye of the bomb in vertically aligned relation above a suspension hook or latch for engagement therewith. During rotation of the drums level

2

winding friction rollers having peripheral speed greater than that of the drums assures uniform distribution of the cable coils in tight engagement with the drums.

3 While the invention is herein shown and described primarily in its application to loading bombs onto an airplane, it is to be understood that such reference is for illustrative purposes, with no intent to unduly limit the scope or application of the invention which is not limited thereto, but is capable of general hoist, drag line operation or other alternative operation.

The object of the invention is to improve the construction as well as the means and mode of 15 operation of hoist apparatus and power operated winches, whereby such apparatus may not only be economically manufactured, but will be more efficient in use, automatic in operation, uniform in action, having relatively few operating parts, 20 and be unlikely to get out of repair.

A further object of the invention is to provide a hoist apparatus or power winch assembly 25 of compact form and relatively light weight, and high power, which may be either portable or permanently installed.

A further object is to provide an apparatus of great strength and rapidity of operation.

A further object of the invention is to provide 30 a hoist apparatus and method of operation, whereby the work load may be raised and lowered under control and while suspended may be turned or rotatively adjusted to an optional extent.

A further object of the invention is to provide 35 vide automatic safety means operative upon failure of either power or manual actuating means, which is operative to maintain the work load suspended in its adjusted position.

A further object of the invention is to provide 40 an improved level winding device for the winding drums by which the cable convolutions are uniformly laid.

A further object of the invention is to provide 45 an improved method of cable control and mode of manipulation of the work load while suspended upon the hoist cable.

A further object of the invention is to provide 50 hoist equipment embodying the advantageous structural features and the inherent meritorious characteristics and the mode of operation herein described.

With the above primary and other incidental objects in view as will more fully appear in the specification, the invention intended to be 55 protected by Letters Patent consists of the fea-

tures of construction, the parts and combinations thereof and the mode of operation, or their equivalents, as hereinafter described or illustrated in the accompanying drawings.

In the drawings, wherein are shown the preferred but obviously not necessarily the only forms of embodiment of the invention,

Fig. 1 is a perspective view of an assembled hoist unit in which the present invention is incorporated.

Fig. 2 is a vertical sectional view thereof.

Fig. 4 is a rear end elevation viewed from the right of Fig. 2 with the housing cover removed, illustrating the driving gear train to the respective winding drums.

Fig. 5 is a detail perspective view of the interlock means between the manual actuating device and the automatic brake.

Fig. 6 is a detail view of the cable anchorage means for connecting the ends of the hoist cable to the respective winding drums.

Fig. 7 is a diagrammatic view of the electrical energizing and synchronizing circuit for the power motors.

Fig. 8 is a side elevation of a modified form of embodiment of the invention.

Fig. 9 is a side elevation partly in section of the embodiment shown in Fig. 8.

Fig. 10 is an end elevation.

Fig. 11 is an electrical circuit diagram of the dual drive synchronizing feature in simplified form.

Like parts are indicated by similar characters of reference throughout the several views.

The present hoist unit is adapted to be either permanently or demountably secured upon an airplane, for operation of its driving motors by current supplied from the power plant of the plane or from the electrical supply system of the air field or other outside source of electrical energy. Heretofore it has required one to several hours to load and secure a large size bomb in the bomb bay of an airplane, whereas by the present power operated unit it is possible to hoist and secure such bomb in a comparatively few minutes. This time factor is highly important when a plane has returned for replenishment of its bomb supply in the midst of an aerial engagement, or when the landing field or bomb supply station is under bombardment. Under such conditions, the interruption of the power current to the motors or injury or death of the operator would prove disastrous in the event a partially raised bomb was allowed to drop. This is prevented by present automatic safety devices. The ability to manipulate or turn the bomb or other load while suspended in elevated position is highly advantageous.

Referring to the drawings, 1 is the main frame of the unit, at the rear of which is a gear housing 2 for the speed reducing transmission gear trains, while at the lower portion of the frame are two forwardly projecting motor housings 3. Immediately above the motor housings are two forwardly projecting conical hubs 4 to support the winding drums.

Within each of the motor housings 3 is a rotor shaft 5 journaled in bearings 6-6. Carried thereon is the motor armature or rotor 7, which is surrounded by the usual stator ring 8 having customary windings 9. The motor is of the reversible type and adapted to optionally drive the corresponding winding drum in either direction.

At its rear end the rotor shaft 5 carries a driving gear pinion 10, which meshes with a gear wheel 11 mounted upon a short shaft 12 journaled in bearings 13 in the walls of the gear housing. The shaft 12 also embodies a gear pinion 14 with which intermeshes an idler gear 15 mounted upon a second short shaft 16 journaled in bearings 17 also in the walls of the gear housing. The intermediate shaft 16 is formed with an integral gear pinion 18, with which intermeshes a driven gear 19 secured to the revoluble winding drum shaft 20 which extends axially through the tapered hub or large boss 4 in which it is journaled. Secured to the forward end of the driven shaft 20 for unison rotation is a winding drum 21 which surrounds and encloses the conical hub 4. The winding drum is provided with a helical peripheral groove to receive one end of the hoist cable 22.

There are two driving motors, as described, and two driven winding drums. Separate power transmission systems connect the respective electric motors with the driven drums. The construction is such that the winding drums 21 are normally driven in unison, preferably in reverse directions to simultaneously retrieve or pay out the opposite ends of the common hoist cable 22. The cable lengths are preferably extended in close relation from the adjacent sides of the drums.

To insure uniform distribution and contact of the cable 22 about the respective winding drums 21, each drum is provided with a level winding device or cable retainer comprising a frictional roller 23 having a resilient peripheral face which contacts and rides upon the convolutions of the cable 22 about the winding drum. Each roller 23 is mounted in an oscillatory frame 24 pivoted at 25 and having an upwardly extending arm 26. Interposed between the rock arms 26 of the oscillatory roller frames is a tensioned thrust bar 27 comprising two axially adjustable sections between which a helical tension spring 28 is interposed. The reaction of the tension spring 28 tends to oscillate the roller frames 24 in opposite directions to press the rollers 23 against the cable turns about the respective winding drums.

The rollers 23 are geared to the winding drums for unison rotation but at an increased peripheral speed. Each drum has at its rear end an integral gear 29, which meshes with a gear pinion 30 secured to the end of the corresponding roller 23, but of less pitch diameter than the diameter of the roller. As a result thereof, each roller 23 is afforded a wiping action upon the convolutions of the cable 22 about the corresponding drum. The surface of the roller being resilient is somewhat distorted or flattened against the drum under the reaction pressure of the spring 28, as is shown in Fig. 3.

The terminal ends of the cable 22 are fixedly secured to the respective winding drums 21. Each drum is formed with a terminal shoulder 31 over which the end of the cable is inwardly extended at 32. The end of the cable is formed into an eye 33 which is securely bolted to a lug 34 integral with the drum. In spaced relation with the cable shoulder 31 is a notch or recess 35 in the terminal margin of the drum which is bridged by the final turn of the cable. A cable clamp 36 comprising a strap of metal reversely bent upon itself into a bight is engaged about the cable within such notch or recess, and the overlapped ends of the

metal strap are clamped to the end of the winding drum shaft 20 by the retaining nut 37.

The cable 22 is conducted from the winding drums 21 in any desired direction and to any necessary extent over suitably placed guide blocks or sheaves 38, and is formed into a medial dependent bight within which the work load is engaged. The medial cable bight preferably comprises a sling 39 especially adapted to the load to be hoisted, but may be merely a continuing bend of the cable 22.

The start, stop and reverse of the motors is controlled from a distant point by suitable switches and circuit breakers in the motor energizing circuit. Upon unison operation of the electric motors to drive the respective winding drums in winding direction, the standing portions of the cable bight 39 are uniformly retrieved to shorten and hence elevate the cable bight 39. Upon reverse operation of the motors in unison, the bight 39 is lengthened and the work load is lowered.

Conventional bombs have therein longitudinally aligned eye bolts 40 by which the bomb is to be suspended from release hooks or latches 41 in the bomb bay of an airplane. When the bomb is initially engaged within the bight or sling 39 of the cable, the eye bolts may be in any position of rotation of the bomb. That is, they may be disposed laterally, vertically, or at any inclination, and so not in proper relation for engagement with the suspension hooks or bomb release latches.

When the bomb has been lifted to a position with its top above the level of the hanger hook or latch 41, the drums are differentially actuated by retrieving only one side or the other of the cable bight, while maintaining the other winding drum at rest, or by retrieving one side of the cable bight while paying out the other side by reverse action of the drums, the bomb is made to rotate about its longitudinal axis to sufficient degree to present the hanger eye 40 in vertical alignment above the suspension hook 41, whereupon by lowering the bomb by unison operation of the drums to pay out the cable ends uniformly, the bomb is lowered until the suspension hook enters the hanger eye of the bomb.

The same method of rotative manipulation of the load may be employed for other purposes, as for example when stowing cargo in a ship's hold, to fit the load relative to previously placed cargo, or for loading equipment onto a truck or car so that it may set level on its bottom or side, as found expedient. Such manipulative action is highly useful in many other non-military operations.

For the purpose of maintaining the cable and work load in adjusted position when the motive power is disconnected, and especially in the event that the source of current supply is destroyed or the energizing circuit accidentally interrupted, each of the actuating motors is provided with an electrically controlled automatic brake. The brake is held in ineffective position by electromagnetic influence until interruption of the current supply occurs. Immediately such brake becomes effective under spring influence to hold the motors and winding drums against rotation. Located within the forward end of each of the motor housings 3 is a partition wall 42 in which one of the shaft bearings 6 of the rotor shaft 5 is disposed. The partition 42 includes a hub 43 concentric with the shaft 5. Mounted on the hub 43 is a recessed electromagnet core 44, having therein a winding 45 which is connected into the motor circuit.

Associated with the core member 44 is an annular armature plate 46 axially movable relative

thereto and attracted toward the electromagnet against the tension of a series of helical springs 48. The armature plate is guided in its to and fro motion and held against rotation by a series of studs 47 sliding in bores in the hub 43. Disposed in parallel relation with the armature plate 46 is a normally fixed back plate or abutment 49. The back plate 49 adjustably mounted on a screw sleeve 50 for axial adjustment, is held against rotation by a stud or pin 51 extending through the plate 49 adjacent the periphery thereof.

Intermediate the armature plate 46 and the back plate or abutment 49 is interposed a friction disc 52 mounted on hub 53 secured to the motor shaft 5, for unison rotation but axially adjustable relative thereto. The friction disc may rotate freely between the armature plate 46 and abutment 49 in unison with the shaft so long as the electromagnet is energized and the armature plate remains attracted thereby against the tension of the springs 48. However, when the electrical circuit is interrupted, thereby de-energizing the electromagnet, the springs 48 forcibly press the armature plate against the friction disc and clamp the latter against the abutment plate. This serves to frictionally lock the motor shaft against rotation, and with it the related driven winding drum, whenever for any reason the supply of electric current is interrupted. The automatic application of the brake will hold the load in its elevated position and will prevent dropping of the bomb or other suspended body.

Upon accidental interruption of the current supply, the loading of a bomb or other hoist operation may be continued by manual actuation of the hoist apparatus. To enable such emergency operation, there is provided on each motor housing head a supplemental housing or gear cover 54 in which is mounted for relative reciprocating motion a rotary shaft 55, having at one end thereof a crank handle 56. The shaft 55 carries a bevel gear 57 which is movable into and out of intermeshing relation with a mating gear 57' upon the end of the motor shaft 5, by the reciprocation of said shaft 55. The shaft 55 is automatically retracted to disengage the bevel gears 57-57' by a helical spring 58 surrounding the shaft, and is temporarily held in operating position by a pivoted latch 59 engageable in a peripheral groove 60 in the shaft 55. The crank shaft detent is controlled by adjustment of the brake back plate or abutment 49 to set or release the brake.

Secured to the screw sleeve 50 upon which the abutment or back plate 49 is mounted is a manual adjusting lever 61 by which the screw sleeve may be partially rotated against the tension of a retracting spring 62 coiled about the projecting end of the screw sleeve with one end attached to the hand lever 61 and the other end anchored to the motor housing.

Loosely journaled on the screw sleeve 50 adjacent to the brake hand lever 61 is a collar 63. At one side thereof is a radial finger 64 to which is connected one end of a helical retractile spring 65, the opposite end of which is connected with the brake lever 61. At its top the collar 63 has therein an elongated notch 66. Adjustably secured to the hand lever 61 is a plate 67 having therein a stud 68 which projects within the elongated notch and serves by engagement with one side of the notch to retract the collar through a partial rotation upon oscillation of the hand lever under retractive influence of the coil spring 62. The elongated notch 66 enables the lever 61 to be

moved through a limited range of adjustment independently of the collar, against the yielding resistance of both springs 62 and 65. The stud carrying plate 67 is adjustable relative to the hand lever by means of the clamp screws 69, whereby the position of the stud 68 may be changed and with it the rotative adjustment of the collar 63 relative to the hand lever. To maintain the radial relation of the plate 67, it is bifurcated and disposed in straddle relation with the sleeve 50.

Opposite the spring engaging finger 64 the collar 63 carries a radial arm 70 which is oscillated with the collar. At its extremity is a hole 71 into which projects a reduced end 72 of the pivoted crank shaft latch 59. The latch plate 59 has therein a key hole slot 73, the medial enlargement of which is of sufficient size for the crank shaft to pass longitudinally therethrough. The terminal slots of the opening 73 have width substantially equal to the neck of the shaft within the peripheral groove 60 thereof.

The crank shaft has a reduced end 74 of the same size as the reduction within the peripheral slot 60, affording a terminal shoulder upon the shaft. The retraction of the brake lever 61 and collar 63 under influence of the springs 62 and 65 elevates the arm 70 and normally holds the latch plate 59 elevated incident to engagement of its end 72 in the hole 71 of the arm 70. The reduced end of the crank shaft is thus engaged in the lower extension of the key hole slot 73. In this relation the lower margin of the key hole slot of the latch plate overlaps the terminal shoulder of the crank shaft to normally prevent longitudinal thrust movement thereof necessary to interengage the bevel gears 57-57'. The manual actuating means is thus locked in inoperative condition. The crank shaft is unlocked by manual adjustment of the brake lever 61 to a mid-stroke position. The collar 63 being partially rotated by the spring 65 as the lever is initially moved, lowers the arm 70 and with it the latch plate until the medial enlargement of the key hole slot is aligned with the crank shaft. The crank shaft is then manually thrust longitudinally through the key hole slot of the latch plate against the yielding resistance of the spring 58, until the peripheral groove 60 of the shaft is in the plane of the latch plate 59. Upon further oscillation of the brake lever, the upper margin of the medial enlargement of the key hole slot is depressed into the peripheral groove 60 of the shaft, thereby locking the latter against retraction under influence of the spring 58, so long as the brake lever is manually held in its finally operated position. During such further and final movement of the brake lever, the arm 70 and the collar 63 are held against further rotation by the described locking engagement of the latch plate with the crank shaft while the stud 68 continues to advance within the elongated marginal notch 66. Such further movement of the brake lever retracts the brake back plate or abutment 49 by partial rotation of the screw sleeve 50 and releases the brake. The operated position of the several parts is shown by the right hand assembly in Figs. 1 and 3.

The engagement of the latch plate 59 within the peripheral groove 60 temporarily locks the bevel gears 57 and 57' in intermeshing engagement, and the winding drums may be rotated by manual effort. However, upon release of the brake lever, which may be intentional or accidental, the brake lever is immediately returned to its original position, the latch is disengaged

and the crank shaft retracted by the spring 58 to its original position, and by reverse rotation of the screw sleeve 50 incident to return of the lever 61, the brake mechanism is automatically reset to arrest and hold the winding drums and the suspended load in their adjusted positions. Thus, in event that the operator is injured or killed while manually operating the hoist, and the brake lever is so released, it operates as a safety device to prevent dropping the bomb or other load.

Likewise, the control switch for the power drive mechanism is preferably one which automatically opens the motor circuit upon release, and such that the motor continues to operate only so long as the control switch is held closed. Therefore, release of the control switch or a break in the energizing circuit will effect automatic operation of the brake to arrest and hold the winding drums and the suspended load.

In Figs. 8, 9 and 10 is shown a modification wherein the dual winding drums are disposed in axial alignment with each other and are actuated by a single driving motor, which may be connected at will with the driving drums independently or simultaneously through associated worm gear drive mechanism which is automatically effective to hold the drums and suspended load in operated position.

Referring to Figs. 8 and 9, the peripherally grooved winding drums 75-75 are mounted for rotation upon a hollow shaft 76 secured in upstanding end frames 77. Connected with each of the drums is a worm wheel 78 which meshes with a worm 79 upon a vertical shaft 80 in the end frame 77. Beneath the drums 75 is an electric motor 81, to the opposite heads of which the end frames 77 are secured. The vertical shafts 80 carry at their lower ends worm wheels 82 with which mesh driving worms connected to the motor shaft 83 by intermediate driving clutches 84. The clutches 84 are separately operable by manual levers 85 to individually connect the respective winding drums with the motor. The hoist cable is arranged as before described, with its ends wound upon the respective drums and a dependent bight in the intermediate portion in which the load to be lifted is suspended.

By simultaneously retrieving the cable uniformly upon both winding drums, the load is lifted or conversely lowered by uniformly paying out the cable from both drums. However, by driving the drums differentially, the load may be rotated to greater or less degree as it is being raised or lowered. In the event of power failure, a hand crank may be applied to the motor shaft at 86 for manual actuation.

As hereinbefore described, it is variously necessary during operation to employ either of the two motors, which are series wound, independently or to operate the motors simultaneously. During simultaneous operation, it is highly desirable, for reasons heretofore explained, that the motors operate at synchronous speeds. This necessitates an equalizing system, the operation of which is delayed until the armature potential of the respective motors reaches a predetermined value. In the event it becomes necessary to start one motor while the other is operating at normal speed, if the equalizing circuit is closed at the moment the second motor is energized, momentarily there would occur a large difference of potential between the respective motor circuits and a heavy flow of current through the equalizing circuit. This would likely result

in a destructive flash or arc at the relay contact point, as well as at the brushes of the motor being started. By delaying the closing of the relay contact until the armature potential reaches a predetermined value, the potential difference is reduced to a safe value and equalization occurs without arcing.

Referring to the accompanying circuit diagrams, wherein 7 and 7' indicate the armatures of the series wound direct current motors 7—8—9, of which 9 and 9' are the field windings, relay coils 87 and 87' are shunted across each motor armature. Circuit make and break contacts 88 and 88' controlled by the relay coils are included in a paralleling circuit line interconnecting the respective motors. The clutch control coils 43 are connected in parallel with the respective motor circuits. The motors are independently controlled by distantly located double throw switches 89 and 89', which according to the direction of operation serve to reverse the rotation of the motors.

When a single switch 89 or 89' is closed, the corresponding series motor will operate at a speed dependent upon the load and speed torque characteristic of the motor. The corresponding relay 87 or 87', as the case may be, being connected across the armature circuit and designed so that its contact 88 or 88' closes only when the potential across the armature reaches a predetermined value, cannot alone close the paralleling or equalizing circuit in which both circuit closers 88 and 88' are included. Consequently, the paralleling operation is not completed while either motor is being operated singly. When, however, both motors are placed in operation, each relay 87 and 87' is energized as soon as the potential across its associated armature reaches the predetermined value. Upon closing both relay contacts the paralleling circuit is completed and the potential across the respective motor armatures is equalized.

The respective motors have similar characteristics, but may be unequally loaded. Under such condition, if not equalized there may be a distinct difference between the speed of the respective motors due to speed torque characteristics of series wound motors. The paralleling operation effected by closing of both relays tends to equalize not only the potential across the armatures, but that across the series fields as well. Thus, the motors are made to operate at substantially equal speeds, even though the loads on the two motors may differ. The current flow through the equalizing circuit will vary with the difference between the loads imposed upon the respective motors. In Fig. 11 the equalizing system is shown reduced to its fundamental form for clarity and ease of understanding.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute, the invention has been described in language more or less specific as to structural features, it is to be understood that the invention is not limited to the specific features shown, but that the means and construction herein disclosed comprise the preferred form of several modes of putting the

invention into effect, and the invention is therefore claimed in any of its forms or modifications within the legitimate and valid scope of the appended claims.

Having thus described my invention, I claim:

1. A hoist apparatus wherein dual independently operable winding drums control a hoist cable common thereto the ends of which are wound upon the respective drums and having a medial bight therein to receive a work load are driven by electromotive means in unison in either direction to raise and lower the work load and differentially to rotate the work load while suspended in said bight, electrically operated power means for the drums, an electrical energizing circuit for said electro-motive means, a manual actuating device for driving the drums independently of the electromotive means, an automatic brake mechanism for arresting and holding the winding drums and suspended load in adjusted position, electromagnetic means for temporarily maintaining the brake mechanism in ineffective condition during operation of the electromotive drive means, and permitting automatic reengagement of the brake mechanism upon interruption of the electric current supply through said circuit, and a manual control device for maintaining the brake mechanism in ineffective condition independently of the electromagnetic means during operation of the manual actuating device for the drums, the brake mechanism being automatically reengageable upon release of the manual control device, the construction and arrangement being such that upon failure of either the electric power supply or of the operator while manually actuating the drums, the brake mechanism is automatically engaged to prevent retrograde motion of the winding drums and suspended work load.

2. A hoist apparatus including a revolvable winding drum, a hoist cable, a portion of which is wound upon the drum, an electric motor and hand crank for actuating the drum alternately at will, an electrical control circuit for the motor, an electrically controlled brake maintained in inoperative condition by influence of electric current in the motor circuit and operative to arrest and hold the drum in operated position upon interruption of the motor circuit, a manual control device for temporarily holding the brake in ineffective relation independently of the electric current influence, and an interlock mechanism between the manual brake control and the hand crank, the construction and arrangement being such that the hand crank is effective only while the brake is manually held in ineffective relation and is automatically rendered ineffective upon release of the manual brake control device.

3. A hoist apparatus wherein a pair of independently revolvable winding drums control a hoist cable, the opposite ends of which are wound upon the respective drums and has a medial bight formed therein, separate electric motors for independently driving the respective winding drums, an electrical energizing circuit for the electric motors by which the operation of the motors is synchronized, manual actuating means for driving the drums independently of the electric motors, brake mechanism effective to hold the drums at rest intermediate periods of operation thereof either by electric motor or manual driving devices, and interlock means for preventing operative engagement of the manual actuating device until the brake mechanism is disengaged and for automatically disengaging the

manual driving devices upon reengagement of the brake mechanism.

4. The herein described method of hoisting a bomb having a suspension eye into a bomb rack of an airplane or the like, having a suspension detent with which the eye of the bomb is engageable, including engaging the bomb in a bight of a hoist cable, retrieving the ends of the cable bight in unison until the bomb is elevated to a position wherein its suspension eye is above the level of the suspension detent, differentially adjusting the ends of the cable bight to effect rotating motion of the bomb therein until the eye of the bomb is in vertical alignment above the suspension detent, and slackening off the ends of the cable bight in unison and thereby lowering the bomb until the suspension eye thereof is engaged by the detent.

5. A bomb hoist or the like including a pair of winding drums, individual motive means therefor, means for driving the drums synchronously or differentially at will, a hoist cable the opposite ends of which are wound upon the respective drums within a medial bight of which a bomb to be hoisted is engageable, the construction and arrangement being such that by unison rotation of the drums the cable is retrieved to hoist the bomb, and by differential rotation of the drums the hoisted bomb suspended in the bight of the cable is rotated therein until the bomb is positioned for engagement with an elevated support, whereupon reverse unison rotation of the drums will transfer the bomb load from the cable bight to said support.

6. A hoisting apparatus, wherein two independently reversible winding drums are driven by separate electric motors, each including an armature and alternately usable field windings arranged to actuate the armature in alternate directions, including an electrical energizing circuit for each motor, an electrically controlled brake mechanism for holding each drum in operated position, an electrical circuit for each brake mechanism disposed in parallel relation with the corresponding motor circuit, a switch common to the motor and brake circuits for simultaneously opening and closing said circuits and alternating the brake circuit in parallel with the respective field windings, and a synchronizing circuit interconnecting the respective motor circuits including two relay switches, one associated with each motor circuit and responsive to predetermined potential thereof, the closing of both of which relay switches operate to equalize the potentials of the respective motor circuits under unequal resistance of the winding drums.

7. In an apparatus of the character described, wherein dual electric motors are adapted for independent or simultaneous operation, a pair of series wound motors, including armature and field windings and energizing electrical circuits therefor, and an equalizing circuit interconnecting the energizing circuit of one motor with that of the other motor, including two electrical switches therein, the energizing coils of which are bridged across the armature windings of the respective motors, and operative only when the electrical potential across the corresponding armature has reached a predetermined value.

8. A hoist apparatus including optionally selective power operated and manual actuating means for operating a pair of winding drums in unison or differentially at will to control a hoist cable, the opposite ends of which are wound upon the respective drums having therein a work engaging

bight wherein a work load may be raised or lowered by unison operation of the drums, and wherein the work load may be rotatively adjusted by differential operation of the drums, including cable distributing devices for effecting uniform distribution of the cable turns on the respective drums to maintain the effective diameters of the drums and cable turns thereon equal, and automatic brake means for arresting the drums to prevent descent of the work load in event of failure of either the power operated or manual actuating means.

9. A hoist apparatus, wherein actuating means is optionally operable for rotating a pair of independently revolvable winding drums, in unison or differentially to control a hoist cable, the opposite ends of which are wound upon the respective drums, and having a medial work load supporting bight whereby the work load may be raised or lowered by unison operation of the drums and rotatively adjusted by differential operation thereof, including cable turn distributing means for maintaining the effective working radii of the drums and accumulated cable turns thereon substantially equalized, and automatic brake means for preventing retrograde rotation of the drums in event of failure of the actuating means therefor.

10. A hoist apparatus wherein driving means is operable optionally to rotate a pair of revolvable winding drums, in unison or differentially to thereby control a hoist cable, the opposite ends of which are wound upon the respective drums having therein a medial bight in which a work load may be supported, the construction and arrangement being such that by unison rotation of the drums the cable ends are uniformly retrieved or paid out to raise or lower the work load in accordance with the direction of rotation of the drums, and by differential rotation of the drums the work load may be rotatively adjusted, characterized by the combination therewith of means for maintaining the effective radii of the drums and accumulated cable turns substantially equal, including rotary power driven frictional cable wiping devices, one for each drum operative to uniformly lay the turns of the cable as they are being wound on the drums.

11. A hoist apparatus, wherein actuating means is provided for optionally rotating a pair of winding drums in unison or differentially to control a hoist cable, the ends of which are wound upon the respective drums having therein a medial work supporting bight, the construction and arrangement being such that the work load may be raised or lowered and may be rotatively adjusted by rotation of the drums, characterized by rotary control means for maintaining the effective radii of the respective drums with accumulated cable turns thereon substantially uniform, including driving means therefor for rotating the control means at a peripheral speed greater than that of the drum whereby the cable control means will exert a wiping action upon the cable in either direction of rotation.

12. In a hoist apparatus wherein a load is supported in a bight of a hoist cable, the opposite ends of which are wound upon separate winding drums revolvable in unison, wherein the piling of cable turns on one of the drums incident to uneven winding thereof will cause the sides of the cable bight to be retrieved differentially with corresponding disturbance of the equilibrium of the load, a level winding device associated with each winding drum and automatically operative during

rotation thereof to maintain the effective diameter of the winding drums substantially equal and the equilibrium of the load constant, including a roller, pressure means for maintaining the roller in contact engagement with the drum, and reversible drive means therefor, the construction and arrangement being such that the peripheral speed of the roller is greater than that of the drum in both directions of rotation.

VICTOR L. DARNELL.
